UNITED STATES PATENT OFFICE

HAROLD B. CRANSHAW, OF NEWTON, MASSACHUSETTS, ASSIGNOR TO BURNITOL MANUFACTURING COMPANY, OF CHARLESTOWN, MASSACHUSETTS, A CORPORATION OF MAINE

RECEPTACLE

Application filed March 17, 1931. Serial No. 523,260.

This invention relates to folded receptacles and particularly to sputum boxes, in which the four sides are noncollapsible, and sputum flasks, in which one pair of opposed sides are collapsible. The principal objects of the invention are to provide a receptacle which may be cheaply manufactured and readily assembled from a single piece of sheet material (with or without an integral cover), which has improved means for interlocking the side portions to prevent collapse or casual separation of its interfolded portions and generally to improve receptacles of the character referred to.

For the purpose of illustrating the genus of the invention a typical concrete embodiment is shown in the accompanying drawing in which

20 Fig. 1 is a plan view of the unfolded blank;

Fig. 2 is a perspective view of the folded receptacle;

Fig. 3 is a section on line 3—3 of Fig. 2; and

25 Fig. 4 is a section on line 4—4 of Fig. 3.

The particular embodiment of the invention chosen for the purpose of illustration comprises a front 1, a back 2, a cover 3, a bottom 4, sides 5 and 6, gussets 7—8, 9—10, 11—12, and 13—14 each pair of gussets constituting one corner divided by a fold line, and flaps 15, 16, 17 and 18 on the gussets 8, 10, 12 and 14 respectively.

One order of procedure in folding the blank of Fig. 1 into the form of the receptacle of Fig. 2 consists in first folding the corner 7—8 against the front 1, then folding the corner 9—10 against the front 1 over the corner 7—8, then folding the flap 15 over the gusset 9 into the space between the gussets 9 and 10, then folding the flap 16 over the gussets 7, 8 and 9 into the space between the front 1 and the first overlapping gusset 7, folding the corner 11—12 against the back 2, then folding the corner 13—14 against the back 2 over the corner 11—12, then folding the flap 17 over the gusset 13 into the space between the gussets 13 and 14, and then folding the flap 18 over gussets 11, 12 and 13 into the space between the back 2

and gusset 11. In this way the corners are easily and effectively interlocked against the back and the front of the receptacle without danger of accidental displacement of the parts.

From the foregoing it will be evident that the corners integrally joining opposite edges of the front or back portions both fold along the same side of said portions respectively. While the corners may fold against either the outer or inner faces of the front and back respectively, for most purposes it is preferable to fold them inwardly as illustrated in Figs. 2, 3 and 4. Thus corner 7—8 folds along the inside of the front and the corner 9—10 then folds along the inside of the front over the corner 7—8; corner 7—8 comprises a first gusset 7 near the front portion 1 and a second gusset 8 overlapping the first gusset more remote from the front 1, 70 with a flap 15 on the second gusset 8 folding inwardly away from the front 1 over the first gusset 9 of the second corner 9—10 into the space between the two gussets 9 and 10, the flap 16 then folding outwardly toward the front 1 over the gussets 7, 8 and 9 into the space between the gusset 7 and the front 1. By cutting off corners of the flaps 15 and 17 to form the oblique edges 19 and 20 all of the flaps may extend substantially across the upper edges of the gusset to which they are integrally attached, thereby interlocking the parts more effectively.

It should be understood that the present disclosure is for the purpose of illustration only and that this invention includes all modifications and equivalents which fall within the scope of the appended claims.

I claim:

1. A blank for a folded receptacle of sheet material comprising a side portion, corners integrally joining opposite edges of said portion, the first corner folding along one side of said portion and the second corner folding along the same side of said portion over the first corner, each corner comprising a first gusset nearer said portion and a second gusset overlapping the first gusset more remote from said portion, and a flap on the first corner folding away from said portion over the first

10. A blank for a folded receptacle of sheet material comprising a side portion, corners integrally joining opposite edges of said portion, the first corner folding along one side 5 of said portion and the second corner folding along the same side of said portion over the first corner, each corner comprising a first gusset nearer said portion and a second gusset overlapping the first gusset more remote from 10 said portion, a flap on the second gusset of the first corner folding away from said portion over the first gusset of the second corner and between the two gussets of the second corner, and a flap on the second gusset of the 15 second corner folding toward said portion over the other three gussets, said second flap substantially spanning the space between said edges.

11. A blank for a folded receptacle of sheet 20 material comprising a side portion, corners integrally joining opposite edges of said portion, the first corner folding along one side of said portion and the second corner folding along the same side of said portion over the first 25 corner, each corner comprising a first gusset nearer said portion and a second gusset overlapping the first gusset more remote from said portion, and a flap on the first corner folding away from said portion over the first 30 gusset of the second corner and between the two gussets of the second corner, said flap being oblique at one end to fit the fold line between the two gussets of the second corner.

12. A blank for a folded receptacle of sheet 35 material comprising a side portion, corners integrally joining opposite edges of said portion, the first corner folding along one side of said portion and the second corner folding along the same side of said portion over the 40 first corner, each corner comprising a first gusset nearer said portion and a second gusset overlapping the first gusset more remote from said portion, and a flap on the second gusset of the first corner folding away from said 45 portion over the first gusset of the second corner and between the two gussets of the second corner, said flap being oblique at one end to fit the fold line between the two gussets of the second corner.

50 Signed by me at Boston, Massachusetts, this 16th day of March, 1931.

HAROLD B. CRANSHAW.
